UNITED STATES PATENT OFFICE.

ERNEST HUTTON, OF FAIRMONT, WEST VIRGINIA.

BLASTING GUN.

Application filed July 24, 1924. Serial No. 727,974.

To all whom it may concern:

Be it known that I, ERNEST HUTTON, a citizen of the United States, residing at Fairmont, in the county of Marion and State of West Virginia, have invented new and useful Improvements in Blasting Guns, of which the following is a specification.

The present invention relates to improvements in blasting guns of the general class adapted for insertion into a blast hole behind a blasting or explosive charge for the purposes of closing the blast hole behind the explosive charge and of firing or exploding such charge, blasting guns of this type being especially adapted for use in the blasting of coal in mines.

The primary object of the present invention is to provide novel and improved means for packing or tamping the space between the walls of the blast hole and the gun, after the latter has been introduced therein, to prevent the gases under the high pressure produced by the explosion of the charge from blowing back along or past the gun, the packing means provided by the present invention enabling the gun to be easily, quickly and effectively packed after it has been inserted into the hole and unpacked with the same speed and facility preparatory to its removal from the hole.

Another object of the invention is to provide a novel and improved surface on the exterior of the gun, such surface being preferably located at a point on the gun between the explosive charge and packing means, such surface acting to catch and hold finely divided or powdery coal or material dislodged by the explosion of the charge and thus causing such material to build up or accumulate and thus fill the space between the wall of the blast hole and the gun, thereby preventing or assisting in preventing the blowing back along the gun of the gases produced by the explosion of the charge.

To these and other ends the invention consists in certain improvements and combinations and arrangements of parts all as will be hereinafter more fully described, the features of novelty being pointed out particularly in the claims at the end of the specification.

In the accompanying drawing:—

Figures 1, 1^a and 1^b represent axial or longitudinal sections of the rear, intermediate and forward portions of a blasting gun

constructed in accordance with the preferred embodiment of the present invention;

Figure 2 represents a cross section through the gun taken on the line 2—2, Figure 1^a; and

Figure 3 is a view similar to Figure 1^a, showing the packing on the gun expanded against the wall of the blast hole.

Similar parts are designated by the same reference characters in the several views.

The present invention is applicable generally to blasting guns of the general class adapted to be inserted into a blast hole which has been previously drilled into the coal or other material to be blasted, behind a blasting charge comprising a suitable explosive, the gun providing means for firing or exploding the blasting charge. Examples of guns of this general class are shown and described in my prior Patent, No. 1,241,386, granted September 25, 1917, and my prior pending application, Serial No. 643,078, filed June 2, 1923. Preferably, the gun serves not only to effect the firing of the blasting charge, but it also serves to pack and close the blast hole, thereby confining the gases resulting from the explosion within the blast hole and preventing such gases from blowing back through the hole and along the gun. The preferred embodiment of the invention is shown in the accompanying drawing and will be hereinafter described in detail, but it is to be understood that the invention is not restricted to the precise construction shown, as equivalent constructions are contemplated, and such will be included within the scope of the claims.

In the present instance, the gun comprises a barrel which may be composed of one or more sections of tubing of steel or other material, the barrel in the present instance comprising a rear tubular section 1, and a forward section 2, a portion of which is preferably reduced in diameter, substantially as shown, and the rear end of the reduced portion of the section 2 may be threaded into the rear section 1, as at 3, or otherwise fixed thereto. The forward portion of the section 2 has a portion 4 which is preferably enlarged in diameter so that it has substantially the same diameter as the rear section 1. The forward end of the section 4 is provided with a head 5 which is adapted to occupy a position immediately adjacent to the blasting charge in the blasting hole, and it

contains means for exploding the blasting charge. In the present instance, the head 5 is adapted to receive and hold a blasting cartridge which is provided with a socket 5 for such purpose, such cartridge being, for example, of the kind fully shown and described in my application executed of even date herewith. For example, the head 5 may be provided with a threaded projection 10 or boss 6 which extends forwardly from its forward end and is adapted to enter a correspondingly threaded socket formed in the base of a cartridge which contains the blasting charge, the cartridge being applied to 15 the forward end of the gun and the gun then serving as means for inserting and placing the explosive charge within the blast hole. As shown, the threaded cartridge receiving projection 6 is formed by the forward end of a plug 7 which is threaded or otherwise fixed within the head 5 on the forward end of the gun. The gun shown in the present instance embodies means for firing blasting charges by percussion, it being 20 understood that the blasting cartridges are provided with percussion primers or caps. Accordingly the plug 7 at the forward end of the gun contains a firing pin 8 which is freely reciprocable in a bore 9 arranged 25 axially within the plug, and the firing pin is provided with a head 10 which may reciprocate freely, within given limits, in a chamber 11 formed within the head 5 immediately in rear of the plug 7. Preferably, a coiled 30 compression spring 12 surrounds the firing pin 8 and bears against the head 10 thereon, this spring serving to normally hold the pin 8 and head 10 in retracted position, as shown in Figure 1^b, the forward end of the firing 35 pin being then in retracted position so that it will not engage the percussion primer or cap for the blasting charge.

Means is provided for driving the firing pin 8 and its head 10 forwardly whereby the 40 forward end of the firing pin will be caused to strike and thereby fire the percussion primer or cap of the blasting charge. As shown, such means comprises a reciprocatory rod 13 which is arranged preferably axially 45 within the gun, its forward end being in line with the head 10 on the firing pin and its rear end, which is normally contained within the rear tubular section 1, may be provided 50 with an eye 14 or other suitable means by 55 which a lanyard or other appropriate device may be attached to it to retract and then release it, thus allowing it to be propelled forwardly within the gun, thus causing its forward end to deliver a blow to the firing 60 pin head 10. The means for propelling the rod or member 13 forwardly comprises preferably a coiled compression spring 15 which surrounds the rod 13, and bears at one end 65 against a collar or shoulder 16 which is fixed to the rod 13, the opposite end of the spring

resting against a guide 17 which may be fixed within the section 1 by set screws 18 or other suitable means, this guide having a central opening through which the rod 13 passes and in which this rod is guided. 70 Means is also preferably provided for normally holding the rod or member 13 in such a position that its forward end is out of contact with the firing pin head 10, so that the latter and the firing pin may be normally held in inoperative position by its spring 12. The means employed for this purpose comprises preferably a coil spring 19 which is of less strength than the spring 15 and bears 75 against the side of the collar or shoulder 16 opposite to the side thereof engaged by the spring 15, the spring 19 resting at its forward end against a suitable fixed stop within the gun, as, for example, the shoulder 20 formed within the rear section 1 of the gun by the rear end of the section 2. The spring 19 will normally hold the reciprocatory rod 13 in the position shown in Figures 1, 1^a and 1^b, the forward end of this rod being 80 then out of contact with the firing pin head and hence danger of premature firing of a blasting charge associated with the gun is minimized or avoided, the forward end of the firing pin being then held by the spring 12 out of contact with the percussion primer or cap of the blasting charge, and the forward end of the rod 13 being held in inoperative position relatively to the firing pin head. 85 In order to fire the blasting charge, when such is intended, it is only necessary to retract the rod 13 by a lanyard or other device attached to its rear end at 14 and to then trip or release the rod in any suitable way, the spring 15 then propelling the rod 90 forwardly so that its rod delivers a hammer blow upon the firing pin head 10, the firing pin being thus driven forwardly in consequence of which its forward end will strike the percussion primer or cap with which the blasting cartridge or explosive charge is provided, thereby causing the same to be exploded. 95 The present invention provides means for packing the space between the gun and the wall of the blast hole, after the explosive charge and gun have been introduced into the hole, and preparatory to the exploding of the blasting charge, for the purposes of confining the gases produced by the explosion to be confined within the blast hole and prevented from blowing back along the gun and to hold the gun in the blast hole in opposition to the force of the explosion. 100 The packing means provided by the present invention is fluid-operated or controlled, so that the packing will be easily, quickly, and effectively expanded against the wall of the blast hole preliminarily to the exploding of the blasting charge, and the packing may be contracted or collapsed with the same speed 105 and facility, after the blasting charge has 110

115

120

125

130

been exploded, thereby enabling the gun to be quickly removed from the blast hole in which the explosion has taken place and inserted in another blast hole. The packing 5 in its preferred form, is shown in the present instance. It comprises preferably a sleeve 21 constructed of a section of tubing of rubber or other appropriate pliable, flexible or elastic material. This tubing is fitted over 10 the reduced portion 2 of the gun and it preferably has substantially the same outside diameter as that of the rear section 1 and the head 5. The ends of the tube or sleeve 21 are secured to the section 2 of the 15 gun so that they will have a fluid-tight fit or joint thereon. For example, the exterior of the reduced portion 2 of the gun may be formed with threads or circumferentially extending grooves 22 at the points in the 20 length thereof which are immediately within the ends of the tubing, and clamping or compressing ferrules 23, which are preferably corrugated, as shown, are provided to clamp or press the respective ends of the 25 sleeve or tubing 21 against the portion 2 of the gun, thereby providing fluid-tight joints which close the ends of the sleeve 21 and prevent leakage of fluid at the ends of the sleeve. One of the ferrules 23 may be attached to the portion 4 of the gun while the 30 other ferrule may be attached to a collar 24, the latter being fitted on the exterior of the portion 2 of the gun and secured in place thereon in any suitable way, as, for example, 35 by the set screws 25. The sleeve or tubing 21 and also the collar 24 may be inserted on the portion 2 of the gun while the latter is detached from the rear section 1.

The packing sleeve or tubing 21 will freely 40 enter the drill or blast hole, designated α when the gun is inserted into the hole, and means is provided for introducing fluid pressure to the inside of the sleeve or tubing 21 whereby the latter will be expanded and 45 thereby forced outwardly from the portion 2 of the gun and against the wall of the drill or blast hole, substantially as is shown diagrammatically in Figure 3, the pliable, flexible or elastic properties of the packing 50 sleeve 21 enabling it to conform with or accommodate itself to irregularities in the surface of the wall of the blast hole, thereby insuring a gas-tight packing of the space between the blast hole and the gun. Preferably, the section 2 of the gun is formed 55 with an axial bore 26 which serves as a passageway for the fluid pressure used, and the portion 2 is formed with a suitable number of outwardly extending ports 27 which lead 60 from the interior bore 26 to the exterior of the portion 2 or the interior of the packing sleeve 21. When compressed air or other fluid under pressure is introduced into the bore or passageway 26 from a hose 28 or 65 other suitable source of supply, such fluid flows longitudinally along the passageway 26, and then outwardly through the ports 27 into the interior of the packing sleeve and the latter, in consequence thereof, is expanded; and when the supply of fluid under 70 pressure is cut off and the fluid is released or permitted to escape from the interior of the packing sleeve, by way of the ports 27 and passageway 26, the packing sleeve is allowed to contract, thereby releasing the 75 gun in the blast hole and permitting it to be easily and quickly removed therefrom after the blasting charge has been exploded. Any suitable means may be provided for admitting the fluid for the purpose of expanding the packing preliminarily to the exploding of the blasting charge and for releasing the fluid and thus allow the contraction of the packing after the blasting charge 80 has been exploded. For example, a valve 29 may be provided on the rear portion of the gun to control communication between the compressed air or fluid pressure supply hose 28 and the passageway 26, and a pressure release valve 30 may also be provided on the rear portion of the gun to allow fluid to be released from the packing and vented to the atmosphere while the supply valve 29 is closed. It will be understood that the release valve 30 is closed while the supply 85 valve 29 is open, and vice versa. In order to allow the reciprocatory rod or member 13 to extend through the portion 2 of the gun without allowing leakage of fluid from the passage 26, a liner 31 is preferably fitted within the bore 26 for the passage therethrough of the rod 13, the ends of the liner being expanded or otherwise fitted as at 32 to provide fluid-tight joints at these points. 90

The present invention also provides means on the gun for preventing or assisting in preventing the blowing back along the gun of gases produced by the explosion of the blasting charge in the blast hole. Such means comprises a surface 33 which is formed preferably on the forward portion 4 of the gun, or on that portion thereof which is between the blasting charge and the packing when such is used. This surface 95 comprises relatively shallow closely related alternating ribs and circumferential grooves or threads with which the exterior of this portion of the gun is provided. Such surface serves to catch or hold the finely divided or powdery coal or other material dislodged by the explosion of the blasting charge, thus causing these particles of material to be built up and accumulate at the points where they are deposited along the 100 length of the gun, the accumulated particles filling the space between the gun and the wall of the blast hole and thus forming, in effect, gas checks which prevent or assist in preventing the blowing back of the gases 105 along the gun. When a surface of this char- 110

115

120

125

130

acter is used in conjunction with packing means located on the gun to the rear thereof, the serviceability of the packing is greatly increased, as the packing is protected to a considerable extent from the high pressure gases produced by the explosion of the blasting charge.

I claim as my invention:—

1. A blasting gun comprising a barrel adapted for insertion into a blast hole, and a fluid-inflatable packing on the exterior of the barrel and adapted to be inflated and thus expanded against the wall of the blast hole.
2. A blasting gun comprising a barrel adapted for insertion into a blast hole, and a fluid-inflatable packing sleeve surrounding the barrel, the latter having means for conducting fluid to said packing to inflate and thus expand it.
3. A blasting gun comprising a barrel adapted for insertion into a blast hole, and a fluid-inflatable packing surrounding and fixed to the barrel at a point intermediate in its length.
4. A blasting gun comprising a barrel, a fluid-inflatable packing sleeve mounted thereon intermediately of its length, and means for conducting fluid under pressure to the interior of the packing sleeve to inflate and thus expand it.
5. A blasting gun comprising a barrel, and a fluid-inflatable packing sleeve mounted on the exterior thereof, the barrel having means for admitting fluid under pressure to the interior of the sleeve to inflate and expand it.
6. A blasting gun having a fluid-inflatable packing sleeve connected by fluid-tight joints at its ends to the gun, and means for

conducting fluid under pressure to the interior of the sleeve to inflate and thus expand it.

7. A blasting gun having a fluid-inflatable packing sleeve of pliable material connected by fluid-tight joints at its ends to the gun, the gun having a passage extending longitudinally within it and communicating with the interior of the packing sleeve to admit fluid under pressure to the interior thereof to inflate and thus expand it.

8. A blasting gun comprising a barrel having a passageway extending longitudinally thereof and a port extending outwardly therefrom, a packing sleeve fitted over the exterior of the gun and connected thereto at its ends, the interior of the packing sleeve communicating with the outwardly extending port, firing means including a rod extending lengthwise through said passageway, and a liner which closes said passageway at its ends and having a longitudinal bore through which said rod extends.

9. A blasting gun comprising a barrel having dust-collecting ribs projecting from its circumference.

10. A blasting gun comprising a barrel having alternately arranged dust-collecting projections and indentations on its circumference.

11. A blasting gun comprising a barrel having packing means located intermediately of its length, and having its exterior surface between said packing means and its forward end formed with indentations to collect and hold material dislodged from a blast hole by a blast therein.

In testimony whereof I have hereunto set my hand.

ERNEST HUTTON.
